Primary Examiner — John R Yeh*(74) Attorney, Agent, or Firm* — Cantor Colburn LLP(57) **CLAIM**

The ornamental design for a brush for vacuum cleaner, as shown and described.

DESCRIPTION

FIG. 1 is a front perspective view of a brush for vacuum cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is another front perspective view in an environment of use;

FIG. 9 is another front perspective view in an environment of use;

FIG. 10 is an enlarged view of the encircled portion 10 in FIG. 4;

FIG. 11 is an enlarged view of the encircled portion 11 in FIG. 5; and,

FIG. 12 is an enlarged view of the encircled portion 12 in FIG. 8.

The even-dash broken lines illustrating portions of the brush for vacuum cleaner form no part of the claimed design. The dot-dash broken lines encircling enlargement portions of the claimed design form no part of the claimed design.

1 Claim, 12 Drawing Sheets(56)
